(57) **CLAIM**

The ornamental design for an intercom display screen for surface mount, as shown and described.

DESCRIPTION

FIG. 1 is a perspective view of an intercom display screen for surface mount, in accordance with an embodiment of the claimed design;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof; and,

FIG. 7 is a bottom plan view thereof.

The portions of the intercom display screen for surface mount shown in broken lines form no part of the claimed design.
